RICHARD LEE DEZENDORF, OF HOLLIS, NEW YORK

GAS METER

Application filed June 4, 1927. Serial No. 196,440.

My invention relates to improvements in gas meters and has for its object to provide a novel and efficient means for adjustably mounting the tangent post upon the tangent 5 of a gas meter so that it may be adjusted angularly with relation to the crank-shaft and also longitudinally of the tangent.

The following is a description of an embodiment of my invention, reference being 10 had to the accompanying drawings, in which,

Fig. 1 is a plan view of a tangent provided with post adjusting means embodying my invention;

Fig. 2 is an enlarged section of the same 15 on the line 2—2, Fig. 1;

Fig. 3 is a section on the line 3—3, Fig. 1;

Figs. 4 and 5 are sectional views showing a modification; and

Fig. 6 is a side elevation showing my in- 20 vention mounted upon the crank-shaft of a meter.

Referring more particularly to the drawings, 2 is the ordinary crank-shaft carrying the worm gear 4 which engages with the 25 driving gear 6 for communicating movement to the ordinary registering train (not shown). 8 is the ordinary tangent mounted upon the shaft 2. 10 is a slide embracing the tangent and adapted to be moved along the same and 30 adjusted in various positions. 12 is a tangent post carried by a member 14 surrounding the slide and through which passes a screw 16 engaging the slide. The screw 16, in the construction shown in Figs. 2 and 4, is held from 35 longitudinal movement relatively to the post carrying member 14 by a collar 18 and has a polygonal head 20 adapted to receive a wrench. This screw passes freely through an opening in the other end of the post-car- 40 rying member and is provided with a lock nut 22 adapted to hold it in fixed position. The member 14 as shown has an opening sur- 45 rounding the slide 10 and preferably also the tangent 8, and can be adjusted upon the slide in a direction at right angles to the axis of the tangent so as to move the tangent post relatively to that axis. The tangent is pro- 50 vided with clamping nuts 24 and 26 which engage the sides of the slide, and where, as shown, the post carrying member surrounds

the tangent, also preferably engages the sides of the post carrying member or yoke. By means of these nuts 24 and 26 the slide, together with the post carrying member, can be adjusted longitudinally of the tangent and 55 clamped in fixed position relatively thereto, so that by means of the nuts 24 and 26 and the screw 16 the tangent post can be adjusted angularly as well as radially with reference to the crank shaft 2.

In the form shown in Fig. 4 the slide is a divided slide and has the advantage that it can be adapted to tangents of varying widths.

In the modification shown in Fig. 5, the 65 screw 28 is provided with collars 30 and 32 which hold it from longitudinal movement relatively to the slide but is movable longitudinally relatively to the post carrying member, being provided with a screw thread 70 34 at one end which makes engagement with a corresponding screw thread in the post carrying member. In this case also a lock nut 36 may be applied to the screw-threaded portion of the screw. In this form the screw pro- 75 trudes from each end of the post carrying member sufficiently to permit the desired adjustment of that member relatively to the slide in either direction.

From the foregoing it will be seen that by 80 turning the screw in one direction or the other the tangent post 12 can be adjusted relatively to the tangent 8 and by the nuts 24 and 26 the slide 10, and consequently the post 12, can be adjusted toward and away from the 85 axis of the crank shaft.

As will be evident to those skilled in the art, my invention permits of various modifications without departing from the spirit thereof or the scope of the appended claims. 90

What I claim is:

1. In a gas meter, the combination of a crankshaft, a screw-threaded tangent thereon, a member embracing said tangent, clamping nuts upon said tangent for adjusting 95 said member longitudinally thereon, a tangent-post-carrying member embracing said first member and an adjusting screw engaging said two members and adapted to adjust them relatively to one another so as to vary 100

the position of the tangent-post relatively to the axis of said tangent, said screw extending across and at one side of said tangent.

2. In a gas meter, the combination of a crankshaft, a screw-threaded tangent thereon, a member embracing said tangent, clamping nuts upon said tangent for adjusting said member longitudinally thereon, a tangent-post-carrying member embracing said first member, and an adjusting screw carried by one of said members and making screw-threaded engagement with the other, said screw extending across and at one side of said tangent.

3. In a gas meter, the combination of a crankshaft, a screw-threaded tangent thereon, a member embracing said tangent, clamping nuts upon said tangent for adjusting said member longitudinally thereon, a tangent-post-carrying member embracing said first member, and an adjusting screw carried by said post-carrying member and making screw-threaded engagement with the other member, said screw extending across and at one side of said tangent.

4. In a gas meter, the combination of a crank shaft, a screw-threaded tangent thereon, a member embracing said tangent, clamping nuts upon said tangent for adjusting said member longitudinally thereon, a tangent-post-carrying member embracing said first member and also said tangent, and screw-threaded adjusting means engaging said two members and adapted to adjust them relatively to one another so as to vary the position of the tangent post relatively to the axis of said tangent, said screw-threaded adjusting means extending across and at one side of said tangent.

5. In a gas meter, the combination of a crankshaft, a screw-threaded tangent thereon, a member embracing said tangent, clamping nuts upon said tangent for adjusting said member longitudinally thereon, a tangent-post-carrying member embracing said first member and also said tangent, and a screw carried by said post-carrying member and making screw-threaded engagement with said other member, said screw lying without the plane of said tangent.

6. In a gas meter the combination of a crank shaft, a screw-threaded tangent thereon, a block embracing and mounted to slide on the tangent, means for adjusting said block longitudinally of the tangent, a tangent post-carrying member embracing said block and an adjusting screw carried by said post-carrying member and making screw-threaded engagement with the block, said block being made in sections adapted to be adjusted to accommodate tangents of different sizes.

7. In a gas meter the combination of a crank shaft, a screw-threaded tangent thereon, two members mounted on said tangent, one of said members carrying a tangent post

and the other member being so formed that it is held from movement transversely of said tangent by engagement with the tangent, and a screw mounted to turn and held from axial movement in one of said members and screw-threaded through the other member for adjusting the tangent post transversely of said tangent, and means for adjusting both of said members longitudinally of the tangent and holding them in adjusted position.

In testimony whereof, I have signed my name to this specification this 2nd day of June, 1927.

RICHARD LEE DEZENDORF.
